United States Patent Office.

WILLIAM WEAVER, OF PHENIXVILLE, PENNSYLVANIA.

Letters Patent No. 61,901, dated February 5, 1867.

IMPROVED BED BOTTOM.

The Schedule referred to in these Letters Patent and making part of the same.

TO ALL WHOM IT MAY CONCERN:

Be it known that I, WILLIAM WEAVER, of Phenixville, in the county of Chester, and State of Pennsylvania, have invented new and useful Improvements in Spring Bed Bottoms; and I do hereby declare the following to be a full and exact description of the same, reference being had to the accompanying drawing, making part of this specification, and in which—

Figure 1 is a perspective view of a bedstead with my improved bed bottom attached.

Figures 2 and 3 are detached views of parts hereinafter described.

Similar letters of reference indicate corresponding parts in the several figures.

My invention consists in a novel manner of placing the spiral springs in lateral holes in the bed-frame; in connecting the wires to the springs by means of links, and in keeping the wires apart laterally and at equal distances from each other, by means of loops formed on one or more of the wires which run from the head to the foot end of the bed.

In the accompanying drawings, A may represent the head-beard, and B the foot-board of a bedstead. C C C C are the bed-posts, which are hinged at c to the frame D D¹ D² D³, so that the bedstead can be easily folded, moved, or stored away, whenever desired. Into the sides D D¹ D² D³, of the frame, I bore holes of just sufficient size to admit the spiral springs E, (see fig. 2.) These holes do not go entirely through the frames, but leave sufficient wood between the base of the hole and the inner side of the frame to form a strong bearing for the inner end of the spiral spring. Through this bearing, at its centre, I bore a small hole, a, to allow the curved piece F to easily slide in and out. At the outer end of this piece of wire, F, is a button, f, which holds a washer, i, the washer forming a bearing for the outer end of the spring E. The holes are covered on the outside of the frame by a thin strip of wood, G, which is nailed, screwed, or otherwise fastened to the frame. The inner end of the curved wire F is bent under, so as to form a loop, g, and is connected to the bottom wires H, I, and K, by means of the links L, as shown in figs. 1, 2, and 3. These links consist of short pieces of wire bent into S-shape, one end hooking into the loop g, of the wire F, and the other into the loops h, at the ends of the bottom wires H, I, and K, the last-mentioned loops h being bent under in the same manner as the loop g. The bottom wires I are properly the supporting wires, whilst the wires H act as braces for them, and the wires K serve to hold them laterally in their positions, and at a certain distance from each other. I do not limit myself to any number of either of these wires, for I propose to use more or less of each as circumstances may require. The wire K, passed from the head to the foot end of the bed-frame, is bent over and around each supporting wire I, forming a loop, k, in which the wire I is not only supported or braced, but held in a laterally steady position. It will be readily understood that the curving of the wire F serves a double purpose. Firstly, it naturally follows the line of motion of the bed bottom when any weight is placed on the same, and when the spring is compressed by it, as seen in red lines in fig. 2, thus dividing the strain on the wire F equally over its whole length, while, if the same were straight, most of the strain would be on that point on the wire F just outside of the orifice a, having a tendency to bend and break it. I am also enabled, by thus dividing the strain, to use a much smaller wire than I could do otherwise. Secondly, it keeps the loops g constantly under its curved part, and consequently the link L in a flat position, and the loops h placed similar to the loops g, so that the hook ends of these loops and links can in no case, and by no violent pressing down of the spring bed bottom, catch into and tear the ticking of the mattress, which is frequently the case in wire bottom beds, where no provision is made to prevent it. The links L perform an important service in my bed bottom, as they give elasticity to and prevent the breaking of the wires H, I, and K, on the ends of which, were they directly attached to the loops g, there would be an additional strain when depressed near the loops h, as will be easily understood. By enclosing the springs E in the lateral holes in the bed-frame I am enabled to preserve them much longer than when they are attached on the outside of the frame, as no dust or dirt can settle in their folds, and they are in a great measure protected from the moisture of the atmosphere, which is very apt to corrode and make them brittle. Furthermore, as the springs lie in holes of just sufficient size to hold them, they cannot get out of order or break, having but just room enough to expand fully. The advantages of constructing my bed on the plan proposed, are many. It is easily made and very durable. Should anything give way the repairs can be made in a few moments. If it is necessary to replace a spring the batten or piece G is removed, when the springs are all

exposed to view and easily taken out and replaced. The movement of the bed is perfectly uniform, as by means of the curved wire F and link L, the cross-wires H, I, and K, are kept constantly in a horizontal position, without bending at their ends when pressed down.

Having thus described my invention, what I claim as new, and desire to secure by Letters Patent, is—

The combination of the spiral springs E, curved wires F, provided with buttons f, and loops g, washers i, links L, supporting wires H I, and looped wires K, substantially as and for the purposes described.

WILLIAM WEAVER.
